(57) **CLAIM**

(21) Appl. No.: **29/271,407**

The ornamental design for a “survival coveralls with adjustable limbs,” as shown and described.

(22) Filed: **Jan. 16, 2007**

DESCRIPTION

(51) LOC (8) Cl. **02-02**

FIG. 1 is a perspective view of a survival coveralls with adjustable limbs, showing my new design;

(52) U.S. Cl. **D29/100; D2/743**

FIG. 2 is a front elevational view thereof;

(58) Field of Classification Search **D2/743;**

FIG. 3 is a rear elevational view thereof;

2/456, 457, 2.11, 2.11 R, 2.15; D29/100

FIG. 4 is a left side elevational view thereof;

See application file for complete search history.

FIG. 5 is a right side elevational view thereof;

(56) **References Cited**

FIG. 6 is a top plan view thereof; and,

U.S. PATENT DOCUMENTS

FIG. 7 is a bottom plan view thereof.
